DESIGN FOR A NEEDLE THREADER

Samuel A. de Waltoff, Los Angeles, Calif.

Application September 2, 1944, Serial No. 115,167

Term of patent 7 years

(CL. D3—19)

To all whom it may concern:

Be it known that I, Samuel A. de Waltoff, a citizen of the United States, residing at the city of Los Angeles, in the county of Los Angeles and State of California, have invented a new, original, and ornamental Design for a Needle Threader, of which the following is a specification, reference being had to the accompanying drawing, forming a part thereof.

The figures in the drawing are: Figure 1 is a

top perspective view of a needle threader showing my new design; Figure 2 is a side perspective view thereof; Figure 3 is a view of one end (both ends being identical) thereof; Figure 4 is a sectional view thereof on the line 4—4 of Figure 2.

I claim:

The ornamental design for a needle threader, as shown.

SAMUEL A. DE WALTOFF.
